REGISTER FOR METER PUMPS

Virgil A. Brunson, Grand Rapids, Elmer Verburg, Grandville, and Harold L. Vanden Hoek, Grand Rapids, Mich., assignors to Blackmer Pump Company, Grand Rapids, Mich., a corporation of Michigan

Application August 6, 1954, Serial No. 448,256

5 Claims. (Cl. 222—36)

This invention relates to a register for meter pumps. It is particularly intended to be built as a part of a hand operated reciprocating piston pump for liquid fuel such as gasoline or fuel oil. One of its principal uses is for pumps used to supply the fuel tanks of farm tractors to enable the farmer to keep a record of the amount of fuel used for vehicles not used on the highway for which no sales tax is charged.

The register will record the amount of fuel pumped at each stroke of the piston regardless of whether it be a full stroke or a part stroke which is desirable because in a hand operated piston pump the piston is not always moved a full stroke.

The register is built as a part of the pump and is cheap, compact, and durable. It embodies various novel features of construction and arrangement, reference being had to the accompanying drawings in which:

Fig. 1 is a vertical elevation, with parts broken away, of a pump with the register attached,

Fig. 2 is a fragmentary elevation of parts of the pump with the register removed,

Fig. 3 is an enlarged elevation of the register with parts broken away,

Fig. 4 is a sectional elevation on the line 4—4 of Fig. 3, and

Fig. 5 is a fragmentary section showing parts of the register.

Like reference numbers refer to like parts in all of the figures.

The body 1 of the pump has an inlet chamber 2 and an outlet chamber 3 to which are connected the flow pipes 4 and 5. A cylinder 6 with a piston 7 is located within the body 1 and communicates with the inlet and outlet chambers 2 and 3 by one way valves 8 and 9, those shown being of the conventional flap valve type.

The piston rod 10 extends through a stuffing box 11 and projects outside the body where it is pivotally connected at 12 to a hand lever 13. The lower end of the hand lever 13 has a link connection with the body 1 of the pump by means of an arm 14 which is pivotally connected at 15 to said pump body, the arm 14 being an integral extension from the meter body 16 and the lower end of the lever 13 being pivotally connected with the rear side of said meter body 16 by a pivot pin 17. By this connection, the hand lever 13 reciprocates the piston rod 10 in a straight line while the lower end of the hand lever 13 oscillates in an arc about the pivotal connection 12.

The register body 16 is of shallow cylindrical shape having a bottom 18 and a circular side wall 19. A boss 20 projecting from the bottom 18 supports the pivot pin 17. A central boss 21 projects forwardly from the bottom 18 and has a bore 22 in which is rotatably mounted a shaft 23. The shaft 23 has fixed to it a ratchet disk 24, a pointer hand 25 and a knob 26. A dial 27 surrounds the shaft 23 forwardly of the ratchet disk 24 and the dial is detachably held in place on the circular side wall 19 by suitable attaching means such as a flat spring

2

ring 28 biting into a groove in the sidewall. The dial 27 bears against a collar 29 on the shaft 23 and holds the shaft in place in the bore 22.

The ratchet disk 24 is spaced from the bottom 18 and in this space is a yoke 30 which is pivoted to the bottom 18 on a pivot pin 31. The yoke 30 has an opening 32 which surrounds the boss 21 with ample clearance for pivotal movement of the yoke. Near the lower swinging end of the yoke 30, and on its under side, a groove 10 33 is provided which extends radially from the pivot 31. A sliding block 34 is mounted in the groove 33, the block 34 being pivotally attached to the end of a stud 35 which is mounted on the hand lever 13 a short distance above the pivot pin 17 on which the hand lever 15 pivots. The stud 35 extends through an arcuate slot 36 in the bottom 18 of the body.

An operating pawl 37 in the nature of a leaf spring is attached to the yoke 30 near, but spaced from the pivot 31 and engages the teeth 38 of the ratchet disk 24. A retaining pawl 39 is attached to the sidewall 19 and engages the ratchet teeth 38 to prevent reverse movement of the ratchet disk.

In operating the pump, the hand lever 13 is oscillated in in and out movements which imparts like movements 25 to the piston rod 10 and piston 7. The out movement draws liquid into the cylinder through the inlet pipe 4, which is connected with a suitable source of supply, and the inlet chamber 2, the inlet valve 8 opening to permit passage of the liquid therethrough. On the in movement, 30 the inlet valve 8 closes and the liquid is forced out of the pump through the outlet valve 9, the outlet chamber 3 and the outlet pipe 5 which leads to a suitable container such as the fuel tank of a tractor. The amount of liquid passed through the pump at each stroke of the lever 35 depends upon the length of the stroke. This may vary because the lever 13, being hand operated, may not always be given the full length of its stroke.

As the lever 13 is oscillated about its pivot pin 17, which connects it with the pump body 1 by the link arm 14, the stud 35 will oscillate about the pin 17 and with relation to the register body 16, moving in the arcuate slot 36. As the stud 35 oscillates in this arcuate movement, the block 34 moves with it, sliding in the groove 33 and causing the yoke 30 to swing about its pivot 31.

Swinging of the yoke 30 moves the operating pawl 37 about the pivot 31. The out movement of the lever 13, which draws liquid into the pump, moves the pawl 37 in counter clockwise direction in which it slides over the ratchet teeth 38. In the in movement of the lever 13, which forces liquid out of the pump and into the container, the yoke 30 is swung in the opposite direction in which the pawl 37 grips the ratchet teeth 38 and moves the ratchet disk 24 in a clockwise direction. As the ratchet disk 24 moves, the pointer hand 25 rotates with it, moving in a clockwise direction over the dial 27. The dial may be marked with the desired indicia such as gallons and fractions thereof, to indicate the quantity of liquid passed through the pump.

The ratchet teeth 38 should be a very fine and close 60 together so that small movements of the lever 13 will register on the dial. It is conceived that other one way clutch or gripping means may be substituted for the ratchet teeth and pawl herein shown.

If it is desired to reset the hand 25, as for example to 65 zero, the knob 26 may be rotated in a clockwise direction which will rotate the hand to the desired location on the dial, the pawls 37 and 39 sliding over the ratchet teeth 38 to permit such movement.

This register is economically constructed. Its body with 70 the extending arm 14 serves as the connecting link between the lower end of the lever 13 and the pump body 1. It is an integral part of the pump structure and not

a separate attachment thereto. It serves the purpose of automatically indicating the quantity of liquid passed through the pump by manipulation of the hand lever, whether the lever be operated in full stroke or part stroke and enables the user to keep a record of the amount of fuel used by his power equipment.

The invention is defined by the appended claims which are to be considered as comprehensive of all forms coming within their scope.

We claim:

1. The combination with a liquid meter pump having a cylinder, a piston therein, a piston rod reciprocable in a straight line and a hand lever pivotally connected between its ends to said piston rod, of a register comprising a body pivotally connected with an end of said hand lever, an extension on said body pivotally connected with the body of the pump, a yoke pivotally connected to said register body, means for oscillating said yoke upon oscillation of said hand lever, a dial on said register body, a pointer hand rotatable adjacent said dial, and interconnecting means between said yoke and said pointer hand acting to rotate the pointer hand upon oscillation of said yoke.

2. The elements of claim 1 in which said means for oscillating the yoke comprises a stud projecting from said hand lever spaced from the pivotal connection of the end of the hand lever to the register body and a sliding connection between said stud and a swinging portion of said yoke.

3. The elements of claim 1 in which said means for rotating the pointer hand comprises, a disk connected to rotate with said pointer hand and one way clutch means acting between said yoke and said disk to rotate the disk upon oscillation of the yoke.

4. The elements of claim 3 in which said one way clutch means comprises ratchet teeth on said disk and a pawl connected to said yoke at a point spaced from the pivot of the yoke and said pawl engaging said ratchet teeth.

5. The combination with a pump having a body in which is a cylinder, a piston and a piston rod, of an oscillatable hand lever pivotally connected to said piston rod, a register having a body which has a pivotal connection to said pump body and also having a pivotal connection with said hand lever at a point spaced from the pivotal connection between the hand lever and the piston rod, said register body serving as a connection between said hand lever and the pump body, indicating means on said register and means actuated by oscillation of said hand lever acting to actuate said indicating means.
